UNITED STATES PATENT OFFICE.

NICOLAE ANTONU, OF GALATZ, RUMANIA.

SHIRT COLLAR.

Application filed August 15, 1927, Serial No. 213,084, and in Rumania October 29, 1926.

This invention relates to a shirt collar which is intended to be worn, for instance in the form of a stand-up collar under uniforms, and a closing member for the same.

5 While the ordinary stand-up collar for uniforms must be closed by means of a stud, which has the disadvantage that it is pressed by the pressure of the uniform collar lying above it against the neck of the wearer and 10 constricts it, or by means of tying tapes, the use of which is inconvenient, the collar with closure according to the present invention has certain advantages, one of which is, for instance, that it may be used for all sizes of 15 necks. The closing member is in no way inconvenient, and has no constricting action, on the contrary, it is possible for instance in hot weather, to alter the size of the collar at will, that is, to loosen it. In addition to 20 this, if the collar is made sufficiently long, it may at the same time be converted into a light and simple neck-tie, which is very convenient, because the collar with the tie can be very quickly fastened. A further advantage is 25 that both the collar and the closing member can be made very cheaply.

In the accompanying drawing, the collar with various constructional examples of the closing member is shown.

30 Figs. 1 and 2 showing one constructional form of the closing member, in two views,

Figs. 3 and 4 another constructional form of the closing member in two views, and

35 Figs. 5 and 6 a further constructional form of the closing member in two views.

Figs. 7, 8 and 9 show three ways of using the closing member for fastening collars.

40 Fig. 10 shows the closing member used in connection with collar and cravat or neck-tie, and

Fig. 11 the closing member for tying the neck-tie.

The member A shown in Figs. 1 and 2 which is made of a flat metal or celluloid 45 strip consists of a strip 1, with a flat slot 2, the length of which is the same as the width of the collar and the width of which is about double the thickness of the collar. One end of the strip is forked and is bent in such a 50 manner that the two ends of the fork, each of which is provided with a small ball or the like, 4, extend approximately parallel to the strip 1, and stand away from the strip by about a single thickness of the collar. 55 The closing member 1, according to Figs. 3 and 4 differs from that shown in Figs. 1 and

2 in this, that the slot 2 between the forked ends is open. The closing member according to Figs. 5 and 6 is bent from a piece of wire, so that, between the two symmetrical approximately parallel limbs 1 and 1^a, a slot 2 is formed at the top of which is a widened portion 2^a for receiving the somewhat thicker marginal seam of the collar. The limbs 1 and 1^a are bent over at the opposite end, with 60 rounded corners, through about 90°, forming transverse pieces 5, 5^a which are also bent over with rounded corners towards the limbs 1, 1^a, forming diagonals 6, 6^a the ends 7, 7^a being bent over approximately at right angles 65 to the limbs 1, 1^a. The end portions, 7 and 7^a, may be omitted.

The upper end of the closing member is bent over gently and the wire is at this part flattened out gradually towards the end so 70 as not to be in the way when bending the neck, while the other end is bent over in the same direction as the bend at 2^a and for the same purpose, together with the transverse pieces 5, 5^a such that the parts 6, 6^a and 7, 7^a 75 are off-set with respect to the limbs 1 and 1^a by about the thickness of the wire.

The closing member is used, as shown in Figs. 7, 8 and 9, for fastening collars in the following manner. The collar 8 which may 80 be fixed by means of a stud through the stud-hole 9 at the back to the neck-band of the shirt, after being placed round the neck, is drawn together in such a manner that it is not too tight round the neck, whereupon a 85 closing member, in this case preferably that shown in Figs. 5 and 6, is slipped with the hook end downwards and with its slot 2 over the bent-over ends of the collar which are held by the end, such that the opening 2^a will rest 90 over the seam of the upper edge of the collar. The collar is thus fixed and, by tightening or 95 loosening the free ends of the collar 8^a, 8^b can be adjusted to rest more tightly or loosely 100 against the neck. Thereupon the collar ends are bent over, as shown in Fig. 8, are slipped in under the ends of the hooked-ends 5, 6, 7, or 5^a, 6^a, 7^a of the fastening member and are pulled out straight, whereby the collar is 105 caused to fit firmly. The collar may be worn in this manner, as the ends 8^a, 8^b are pressed down by the uniform collar, but the appearance will be improved by the collar ends being turned over by about 90°, as shown in Fig. 9, 110 under the fastening member, in which position they will cover the member and be held down by the uniform collar.

The collar may be made as a simple strip about 60-70 centimeters long of linen, cotton or cloth of a suitable width, and be provided at a suitable place in the middle with a stud-hole. Thus, it is not only cheap and practical, but also easy to wash and iron.

The collar may also be adapted for civilian use in combination with a neck-tie, as shown in Fig. 10, such that the extended ends which 10 may be tapered towards the end, as shown in Fig. 10, are fastened together by the fastening member, the long downwardly extending ends 8^a, 8^b, which represent the neck-tie, being fixed by means of a tie-pin 10 or 15 in any other suitable manner. This extended collar, just as the uniform collar, has the advantage that it is simple and cheap to make. The loose ends 8^a, 8^b alone, or the collar as well, may be coloured on one or both sides 20 or printed with a coloured design, and thus, in combination with the fastening member, form a cheap, healthy termination to the shirt, which is comfortable to wear and is easily and quickly put on and which is particularly pleasant in the hot part of the year. 25 In the latter case, the fastening member may be so arranged that it can be clamped or suspended in any known manner to the front shirt stud.

30 The extensions 7, 7^a at the end of the fastening member which are bent up in a circular form, also serve the purpose of uniting the collar ends to form a raised plastic knot, whereby the neck-tie is given a more beautiful form.

The fastening member can be used alone very conveniently for fastening neck-cloths, scarves, shawls and the like as is shown in Fig. 11. It does not damage the material as 40 is the case with inserted pins, and the material, when gathered together, can be pulled through under the forked ends or hooks and united to form a rosette, the fastening member being more or less covered.

45 The fastening members shown in Figs. 1 to

4 are used similarly to that shown in Figs. 7 to 11. The closing member may be provided as required with stamped, engraved or attached ornamentations.

What I claim is:

1. A shirt collar and fastening device therefor comprising in combination a strip of material constituting the collar, and a longitudinally slotted member constituting the fastening device, the ends of the collar being adapted to be pulled through the slot in the fastening device, the length and width of which slot substantially correspond to the width and double thickness respectively of the collar, and the ends of the fastening device being bent to form forked hooks, around which the ends of the collar can be folded subsequently to being pulled through the said slot, as and for the purpose set forth. 50

2. A shirt collar and fastening device therefor comprising in combination a strip of material constituting the collar, and a wire, bent to provide parallel limbs with an intervening open-ended slot, constituting the fastening device, the ends of the collar being adapted to be pulled through the slot between the said limbs of the fastening device, the length and width of which slot substantially correspond to the width and double thickness respectively of the collar, and the ends of the fastening device being bent to form Z-shaped hooks, around which the ends of the collar can be folded subsequently to being pulled through the said slot, as and for the purpose set forth. 60

75 3. A shirt collar and fastening device therefor as claimed in claim 2, wherein the Z-shaped hooks are slightly off-set in relation to the parallel limbs of the fastening device so as to facilitate the folding operation of the collar ends which are of such a length and shape as to form a neck-tie, as set forth.

In testimony whereof I have signed my name to this specification.

NICOLAE ANTONU.
